STRIKING BAG MACHINE

John F. Meyer, Pasadena, Calif.

Application February 12, 1932, Serial No. 592,466

9 Claims. (Cl. 265—20)

My invention relates to coin operated amusement machines and its primary object is to provide a novel machine for determining the force of the blow by the operator's foot on an inflated ball in the machine.

An object of the invention is also to provide a novel machine for affording entertainment and information to the operator who kicks the ball as he would in playing the game of football.

Another object of the invention is to provide a machine of novel and simple construction comprising an inflated ball adapted to be kicked by the operator to actuate mechanism for indicating the force of the blow on a conveniently located chart forming part of the machine.

Another object of the invention is to provide means for holding the indicating device in indicating position until the machine is again operated to place the ball in operative position.

Other objects of the invention are to provide means for locking the ball in inoperative position after each operation of the machine, to provide coin operated means for releasing the locking means, and to provide means to insure only one operation of the machine for each coin introduced therein.

In the accompanying drawings in which I have illustrated a selected embodiment of the invention.

Fig. 1 is a front elevation of the machine.

Fig. 2 is a sectional view taken on the line 2—2 of Fig. 1.

Fig. 3 is an enlarged vertical sectional view of the machine mechanism.

Fig. 4 is a transverse sectional view of the ball releasing and coin operated mechanism.

Fig. 5 is a fragmentary view showing the indicator release mechanism and the bumper spring.

Fig. 6 is an enlarged view similar to Fig. 4 but showing the ball releasing mechanism in releasing position.

Fig. 7 is a detail vertical sectional view taken on the line 7—7 of Fig. 6 showing the coin operated mechanism.

Fig. 8 is a detail vertical sectional view of the coin operated mechanism and the chute safety device.

Fig. 9 is an enlarged vertical sectional view of the indicator and showing the indicator locking device, and

Fig. 10 is a transverse sectional view taken on the line 10—10 of Fig. 9 showing in dotted lines the indicator locking device in release position.

Referring to the drawings, a ball 11 preferably

of leather having a separate inflated rubber lining, is mounted on the end of a supporting lever arm 12 pivoted at 13 in a bracket in the base of the machine. An opening 14 is provided in the front of the machine and a slot 15 extends downwardly therefrom to permit movement of the ball and supporting lever arm 12 about the pivot 13. A cushion 16 of rubber, felt, or like material, is provided at the bottom of the slot 15 to cushion the supporting lever arm 12 when it drops into lowered or operative position shown in dotted lines, Fig. 3. When the ball is in the lowered position the operator kicks it thereby pivoting the ball 11 and supporting lever arm 12 about the pivot 13 into raised or inoperative position where the ball strikes the board 17. The board 17 is mounted on the indicator actuating lever 18 which is pivotally mounted to a spacer block 19 at 20. The spacer block 19 is fastened to the machine cabinet by bolts 21. The indicator actuating lever 18 passes through a U-shaped stop 22 which limits the movement of the indicator actuating lever about the pivot 20. A spring 18' holds the actuating lever 18 in normal position and also absorbs part of the blow imparted to the ball 11. The stop device is provided with cushions 23 to absorb the jar and consequent noise resulting from the movement of the indicator actuating lever.

The end of the indicator actuating lever extends beneath a weighted indicator 24 and is bifurcated to receive the indicator guide rod 25 and the indicator cushion 26. The indicator guide rod 25 is mounted on and extends vertically from a bracket 27 on the machine cabinet. The indicator cushion is fastened to the indicator guide rod beneath the indicator. The indicator has the configuration of a football and is slidably mounted on the guide rod 25. A bell 28 is mounted at the upper end of the guide rod and is adapted to be struck by the indicator. A spring pressed pawl 29 is carried on the indicator and is arranged to engage a series of lugs 30 on the rock shaft 31 and thereby retain the indicator in the elevated position to which it has been thrown in the operation of the machine.

A link 32, Fig. 4, has one of its ends pivotally mounted to an arm 33 fastened to and extending from the rock shaft 31. The other end of the link has an elongated slot 34, Fig. 3, therein to receive an end of the pin 35 which is mounted in the supporting lever arm 12. When the ball 11 is placed in its lowered position the pin 35 engages the end of the slot 34 thereby turning the rock shaft 31 to the dotted line position in

Figs. 5 and 10. The lugs 30 are thus turned from under the pawl 29 allowing the indicator to drop to lowered position.

When the ball is kicked by the operator the 5 supporting lever arm swings about its pivot 13 releasing the end of the slot 34 from engagement by the pin 35. The spring 36 fastened to the machine cabinet and to the link 32 then returns the rock shaft 31 to its normal position to place 10 the lugs 30 in the path of the pawl 29.

A block 37 mounted on the machine cabinet carries a bumper spring 38 retained in place in the path of the supporting lever arm 12 by screw 39, Fig. 5, for the purpose of absorbing part of 15 the blow imparted on the ball by the operator.

A coin chute 40 is provided to direct a coin to the coin receiving slot 41 in the coin carrier 42. The discharge end of the coin chute 40 is provided with a side flap 43, Fig. 8, hinged at 44 on 20 the chute. A spring 45 keeps the flap normally closed but in the event that a coin larger than the coin intended to operate the machine is deposited in the chute it will be deposited in the coin receiving slot but will also extend far enough 25 above the slot to be within the end of the chute and a forced movement of the coin will swing the flap open to allow a discharge of the coin without damage to the chute. An operating handle 46, Fig. 1, is placed outside the machine cabinet on the end of the operating rod 47. At the lower end of the operating rod within the cabinet is an operating lever 48 rigidly secured thereto. A slide 49 interposed between guides 50, 51 has a lug 52 mounted thereon for engagement 30 with the operating lever 48. The guides 50 and 51 are connected by links 53 and 54 which are located over the slide 49. The coin receiving slot 41 is formed between the angle 55 fastened to the slide 49 and the coin carrier 42 spaced from bracket 55 by spacer 56. The spacer 56 and the coin carrier 42 are fastened to the angle 55 by the bolt 55' and are carried thereby. The carrier 42 is a plate bent downwardly at 57, Fig. 7, to form one side of the receiving slot 41. The remaining portion of the carrier acts as a stop to 45 halt movement of the coin downwardly out of the chute 40 when the operating handle 46 is operated to move the slide 49 and the receiving slot 41.

A latch 58 pivoted at 59 has a hook portion 60 thereon adapted to engage the supporting lever arm 12 when in its raised position. When the ball is in operative position and a blow is struck thereon as by being kicked by the operator, the ball is forced toward the opening 14, and as the ball moves into its inoperative position in this ball-receiving portion or opening 14, the latch 58 engages arm 12 and limits rebound of the ball to prevent it from moving out of the opening 14 50 after it strikes the board 17. The latch 58 also has a projection 61 adapted to engage a coin 62 in the coin receiving slot 41, as shown in Fig. 6. A spring 63 is adapted to maintain the latch in supporting lever arm locking position.

A spring 64, Fig. 4, is adapted to hold the lug 52 on the slide 49 always in engagement with the operating lever 48. When a coin is deposited in the chute 40 it drops into the coin receiving slot 41 and the operator moves the operating lever 48 by means of a handle 46 the slide 49 will travel to the right, Figs. 4, 6 and 7, and the coin 62 will engage the projection 61 to pivot the latch 58 to remove the hook portion 60 from engagement with the supporting lever arm 12 whereupon the 75 spring 65 will throw the supporting lever arm 12

over the center and allow the supporting lever arm and ball to drop into lowered position.

During the downward movement of the supporting lever arm the pin 35, Fig. 5, will strike the end of the elongated slot 66, Fig. 3, in the link 67 which is pivotally attached to the vertical lever 68 at 69, pulling the link 67 to the right, Fig. 3, and pivoting the vertical lever 68 in the bracket 70 in which it is mounted. The vertical lever 68 strikes the horizontal lever 71 and moves the 10 lever in the slot 73 in its guide 74 until the end of the horizontal lever 71 strikes the end of the slide 49 forcing it further to the right as shown in broken lines in Fig. 6. This further movement 15 brings the coin 62 over the cutout portion 75 in the frame allowing the coin to discharge into the coin receptacle 76. The spring 63 will then return the latch into locking position and the spring 77, Fig. 3, attached to the arm 78 on the operating rod 47, will return the handle 46 to normal 20 position. After the ball has been kicked, the spring 64 returns the slide 49 to normal position. The pin 35 will strike the other end of the slot 66 and return the vertical lever 68 to normal position. The movement of the slide 49 to the lever, 25 Fig. 6, will throw the horizontal lever 71 into normal position.

If no coin is deposited in the chute 40 and consequently no coin being placed in the receiving slot 41, movement of the operating lever 48 30 will move the slide and the coin carrier 42 heretofore described but there will be no motion imparted to the latch 58 as the coin carrier 42 will merely pass over the projection 61 and there will be no engagement thereof to release the supporting 35 lever arm 12. A guard 79 is rigidly fastened to the supporting lever arm 12 for the purpose of preventing an operator from removing the latch from locking position without the insertion of a coin into the machine.

It will be readily seen from the foregoing description that I have provided an amusement machine which may be used to indicate the force of a blow struck on a member of the machine by the operator's foot, and it is apparent that the device 45 is so arranged that the member may be moved into striking position only after the insertion of a coin into the machine. Furthermore it is evident that the parts are returned to inoperative 50 position after the striking of a blow on the member and will not again be placed in operative position until the insertion of a proper coin, and if a coin other than the coin intended to operate the machine is inserted no damage to the machine will result therefrom.

While I have illustrated and described a selected embodiment of my invention it is to be understood that this is capable of variation and modification and I therefore do not wish to be limited to the precise details set forth but desire to avail myself of such changes and alterations as fall within the scope of the following claims:

I claim:

1. In a striking bag machine, an arm carrying 65 a ball adapted to be struck, means pivotally supporting said arm for movement in a plane extending at right angles to the vertical center plane of said pivot means, said arm being movable past the center plane of said pivot means into 70 a lower operative position and an upper inoperative position, a releasable latch engageable with said arm to retain said arm in inoperative position, and means for moving said arm past said center plane upon the releasing of said latch 75

whereby said arm may freely fall into lower operative position.

2. In a striking bag machine including a housing having an opening therein, an arm carrying a ball adapted to be struck, means in said housing pivotally supporting said arm for movement in a plane extending at right angles to the vertical center plane of said pivot means, the center plane of said pivot means being located at one side of said opening in said housing whereby when said arm is moved in said plane said ball may be moved past said center plane to and from said opening, a releasable latch engageable with said arm to retain said arm to locate said ball in said opening, and means for moving said arm past said center plane to remove said ball from said opening upon the releasing of said latch whereby said arm may freely fall into a lower operative position after movement thereof past said center plane.

20 3. In a striking bag machine, a housing including an inclined front wall having an opening therein and a slot extending downwardly from said opening, an arm carrying a ball adapted to be struck, means in said housing pivotally supporting said arm whereby said arm may move through said slot past the vertical center plane of said pivot means to position said ball in an upper inoperative position in said opening on one side of said vertical center plane or in a lower operative position in front of said wall on the other side of said vertical center plane, a releasable latch engageable with said arm to retain said arm to hold said ball in said upper inoperative position, and means for moving said arm past said vertical center plane upon the releasing of said latch whereby said arm may freely fall into said lower operative position after movement thereof past said vertical center plane.

4. In a striking bag machine, indicating means including an actuating part, an arm carrying a ball adapted to be struck, means pivotally supporting said arm for movement in a plane extending at right angles to said pivot means whereby said ball may be moved into a lower position whereat a blow may be struck thereon to pivot said arm in said plane into an upper position to actuate said actuating part, yieldable means engageable with said arm to absorb a part of the movement imparted to said arm when a blow is struck on said ball, and a latch engageable with said arm and cooperating with said yieldable means to retain said arm between said yieldable means and said latch and limit rebound of said arm away from said yieldable means upon engagement of said arm with said yieldable means.

5. In a striking bag machine, indicating means including a strikable part, an arm carrying a ball adapted to be struck, means pivotally supporting said arm for movement in a vertical plane extending at right angles to said pivot means whereby said ball may be moved into a lowered position whereat a blow may be struck thereon to pivot said arm in said vertical plane and engage said ball with said strikable part, spring means disposed in the path of movement of said arm and adapted to be engaged by said arm when a blow is struck on said ball and adapted to absorb a part of the movement imparted to said arm when a blow is struck on said ball, and a latch engageable with said arm and including a retaining part disposed in the path of movement of said arm and movable out of said path by engagement of the arm with the retaining part upon movement of said arm and said ball toward said strikable part and spring means, said retaining part engaging

said arm after said arm has moved past said retaining part to thereby retain said arm between said spring means and said retaining part.

6. In a striking bag machine, an arm carrying a ball adapted to be struck, means in said housing pivotally supporting said arm for movement in a plane extending at right angles to the center plane of said pivot means, said arm being movable past the center plane of said pivot means into a lower operative position and an upper inoperative position whereby a blow may be struck on said ball when it is in operative position to pivot said arm in said plane into said upper inoperative position, yieldable means engageable with said arm to absorb a part of the movement imparted to said arm when a blow is struck on said ball, a latch for retaining said arm in inoperative position after a blow has been struck on said ball and said arm has engaged said yieldable means, and means for moving said arm past said center plane and away from said yieldable means upon the releasing of said latch whereby said arm may freely fall into lower operative position after movement thereof past said vertical center plane.

25 7. In a striking bag machine, indicating means including an actuating part, an arm carrying a ball adapted to be struck, means pivotally supporting said arm for movement in a plane extending at right angles to the vertical center plane of said pivot means, said arm being movable past said vertical center plane of said pivot means into a lower operative position and an upper inoperative position whereby a blow may be struck on said ball when it is in operative position to pivot said arm upwardly in said plane to actuate said actuating part, yieldable means engageable with said arm to absorb a part of the movement imparted to said arm when a blow is struck on said ball and said actuating part is actuated, a latch including a retaining part adapted to be moved out of the path of movement of said arm when a blow is struck on said ball and movable into the path of movement of said arm after movement of said arm past the retaining part to thereby retain said arm in inoperative position after a blow has been struck on said ball and said actuating part has been actuated and said arm has engaged said yieldable means, and means for moving said arm past said vertical center plane and away from said yieldable means upon the releasing of said latch whereby said arm may freely fall into lower operative position after movement thereof past said vertical center plane.

50 8. In a striking bag machine, a housing including an inclined front wall having an opening therein and a slot extending downwardly from said opening, indicating means including an actuating part arranged behind said opening, an arm carrying a ball adapted to be struck, means in said housing pivotally supporting said arm whereby said arm may move through said slot past the vertical center plane of said pivot means to position said ball in an upper inoperative position in said opening on one side of said vertical center plane and in juxtaposition to said actuating part or in a lower operative position in front of said wall on the other side of said vertical center plane, a releasable latch engageable with said arm to retain said arm to hold said ball in inoperative position after a blow has been struck on said ball and said ball has engaged said actuating part to operate said indicating means to indicate the force of the blow struck on said ball, and means for moving said arm past said vertical center plane whereby

said ball may freely fall toward operative position upon the releasing of said latch.

9. In a striking bag machine, a housing including an inclined front wall, having an opening 5 therein and a slot extending downwardly from said opening, indicating means including an actuating part arranged behind said opening, an arm carrying a ball adapted to be struck, means in said housing pivotally supporting said arm where-
10 by said arm may move through said slot past the vertical center plane of said pivot means to position said ball in an upper inoperative position in said opening on one side of said vertical center plane and in juxtaposition to said actuating part
15 or in a lower operative position in front of said wall on the other side of said vertical center plane, yieldable means for absorbing a part of the move-

ment imparted to said arm when a blow is struck on said ball and said ball is driven into said opening and engages said actuating part to operate said indicating means to indicate the force of the blow struck on said ball, a latch engageable with said arm to retain said arm in inoperative position after a blow has been struck on said ball and said actuating means has been actuated and said arm has engaged said yieldable means and adapted to prevent rebounding of said arm, and means for moving said arm past said center plane and away from said yieldable means upon the releasing of said latch whereby said arm may freely fall into lower operative position after movement thereof past said center plane.

JOHN F. MEYER.
